Primary Examiner — Darlington Ly*Assistant Examiner* — Giang Hoang Tran(74) *Attorney, Agent, or Firm* — Kunzler Bean & Adamson, PC; Bryan Pitt(57) **CLAIM**

The ornamental design for a motorcycle storage case, as shown and described.

DESCRIPTION

FIG. 1 is a top, front and left side perspective view of a motorcycle storage case, showing my new design;
FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion labeled “9” in FIG. 1;

FIG. 10 is an enlarged view of portion labeled “10” in FIG. 1; and,

FIG. 11 is an enlarged view of portion labeled “11” in FIG. 3.

The dash-dot-dash broken lines define the boundary of an enlarged view and form no part of the claimed design.

1 Claim, 11 Drawing Sheets(56)
